UNITED STATES PATENT OFFICE.

RUFUS R. ROSS, OF DETROIT, MICHIGAN.

FUEL ECONOMIZER AND DECARBONIZING DEVICE.

Application filed October 17, 1924, Serial No. 744,120. Renewed May 3, 1926.

This invention relates to a fuel economizing and decarbonizing device for internal combustion engines, and my invention aims to furnish an attachment that may be easily 5 and quickly installed on an internal combustion engine to supply heated air, water, steam and oil vapor to the intake manifold connection of the engine, to commingle with the usual supply of fuel and increase its 10 combustion properties and decrease the carbonizing effect of the fuel in the cylinders or combustion chambers of the engine. It is a well known fact that if water, vapor or steam is introduced into the cylinders or 15 combustion chambers of an engine, that carbonizing will be reduced to a minimum, if not completely eliminated, and that the addition of steam and water vapor to engine fuel places it in a better condition for combustion. It is also a well known fact that the introduction of air is beneficial and increases the volume of fuel, while oil vapor provides better lubrication and also contributes towards better combustion, especially when certain fuels are used.

My invention further aims to provide a novel manifold connection that may be interposed between the intake manifold of an engine and the outlet connection of a carburetor, and it is by virtue of my connection that various kinds of vapors can be introduced to commingle with the engine fuel as it passes from the carburetor to the cylinders or combustion chambers of the engine. The 30 manifold connection includes a novel mixing chamber and valve controlled inlet connections. It is by virtue of these inlet connections that the manifold connection is well braced and supported relative to an engine. 35 My invention will be hereinafter specifically described and then claimed, and reference will now be had to the drawing, wherein-

Figure 1 is a side elevation of an internal combustion engine equipped with my device; 40 Fig. 2 is a vertical sectional view of the manifold connection, and

Fig. 3 is a vertical sectional view of the mixing chamber of the manifold connection. 45 In the drawings, the reference numeral 1 denotes a cylinder block having a crank case 2, an exhaust manifold 3, an intake manifold 4, a carburetor 5 having an outlet connection 6, and a throttle 7 in the carburetor outlet connection 6, which throttle is articulated with a pedal arrangement 8 for ad-

justing the throttle. When the engine forms the power plant of an automobile or other driven motor vehicle, the pedal 8 is ordinarily located on the foot board 9 of the 60 automobile and above the foot board is a dash 10, which will again be referred to.

Interposed between the carburetor outlet connection 6 and the intake manifold 4 is the lower angular end 11 of a vertically disposed 65 jacket 12, said jacket extending upwardly at the outer side of the intake manifold 4 with its upper end inturned and provided with a cylindrical head 13 directly above the exhaust manifold 3. The jacket 17 may be made 70 in sections suitably connected together and the lower end of the jacket can be fixed in position without any danger of gas leakage between the carburetor and the intake manifold.

In the jacket 12 and suitably spaced from the walls thereof is a conduit 14 which extends throughout the length of the jacket and has its lower end communicating with the intake manifold 4 and the carburetor outlet connection 6 by a series of upper and lower openings 15, the upper openings alining with the lower openings so that fuel may pass through the lower end of the conduit from the carburetor to the intake manifold 4. The 80 openings 15 serve somewhat as screens or baffles to assist in atomizing the fuel from the carburetor, and since the walls of the openings 15 will be heated from the jacket 12, the fuel passing through the openings 15 will be 85 vaporized.

On the upper end of the conduit 14 within the cylindrical head 13 is a cylindrical mixing chamber 16 having a plurality of radially disposed connections 17 with the head 13 and the connections 17 are preferably four in number. First, there is a connection for an air supply pipe 18 having a valve 19 operable from the dash 10 by a rod 20. Another of the connections 17 communicates with the 95 crank case 2 by an oil vapor supply pipe 21 which has a valve 22 operable by a rod 23 from the dash 10.

Mounted on top of the cylinder block 1 or suitably supported adjacent thereto is a combined water boiler, and steam generator in the form of a water tank or reservoir 24 surrounded by a jacket 25. The jacket 25 has pipe connections 26 and 27 with the exhaust manifold 3 so that the exhausted or burned 110 gases from the engine may circulate through the jacket and heat the walls of the water

reservoir 24 by conduction. On the pipe 26 is a valve 28 operable by a rod 29 from the dash 10.

The water reservoir 24 has a filling connection 30, a safety valve 31 and pressure gauges 32 and 33, the latter being located on the dash 10.

Connecting the top of the water reservoir 24 to one of the connections 17 of the mixing chambers 16 is a steam supply pipe 34 having a valve 35 operable by a rod 36 from the dash 10, and connecting the bottom of the reservoir 24 and another of the connections 17 of the mixing chamber 16 is a water supply pipe 37 having a valve 38 operable by a rod 39 from the dash 10.

The lower end of the jacket 12 is connected by a pipe 40 to the exhaust manifold 3 and the top of the head 13 is connected by a pipe 41 to the exhaust manifold 3 so that exhausted or burned gases from the engine may circulate through and heat the conduit 14 and the mixing chamber 16.

In the conduit 14 is a throttle 42 connected by a link 43 to the carbureter throttle 7 and a rod 44 is connected to the throttle 42, so that the throttles 7 and 42 may be actuated in synchronism by either the pedal 8 or the rod 44.

Since the conduit 14 is heated throughout its length any water admitted to the conduit will be vaporized and vapors, air and steam will be heated, so that when any of these vapors reach the lower end of the conduit they will be in condition to commingle with the engine fuel and pass into the cylinders or combustion chambers of the engine. With all of the mixing chamber connections valve controlled it will be possible for the operator of an automobile to govern the admission of vapors to the intake manifold according to the performance of the engine and according to the fuel used for the engine. Since the beneficial results attained by using various kinds of vapors are known, it is thought that the operation and utility of my device will be apparent without further description, and while in the drawings there is illustrated a preferred installation and construction, it is to be understood that my invention is susceptible to such changes as are permissible by the appended claims.

What I claim is:

1. A device of the character described comprising a jacket for heating purposes, said jacket having an end thereof fashioned for mounting between the outlet connection of a carbureter and the intake manifold of an internal combustion engine, a conduit in

said jacket adapted to be heated by a heating agent in said jacket, said conduit having one end thereof coaxially of said carbureter outlet connection and communicating with said carbureter outlet connection and said manifold by a series of openings so that engine fuel may pass through the end of said conduit, and a mixing chamber at the opposite end of said conduit in said jacket and adapted to be supplied with various kinds of vapor to pass through said conduit and commingle with the engine fuel.

2. A device as called for in claim 1, and a water boiler and steam generator communicating with said mixing chamber and adapted to supply steam and water to said mixing chamber.

3. A device as called for in claim 1, wherein said mixing chamber has radially disposed valve controlled inlet connections.

4. A device as called for in claim 1, and a throttle said conduit adapted for actuation in synchronism with a carbureter throttle.

5. A device as called for in claim 1, wherein said jacket has connections so that engine exhaust gases may be utilized as a jacket heating agent.

6. The combination with a multi-cylinder engine having a crank case, cylinder block, intake and exhaust manifolds, a carbureter adapted to supply fuel to the engine intake manifold, and a throttle for said carbureter, of a jacket having one end interposed between said carbureter and said intake manifold, connections between said jacket and the engine exhaust manifold so that exhaust gases may circulate through said jacket, a conduit in said jacket having its lower end communicating with said engine intake manifold, a throttle in said conduit connected to said carbureter throttle, a mixing chamber at the upper end of said conduit in said jacket, a steam generator, connections between said generator and said exhaust manifold so that exhaust gases may be used as a source of heat for said steam generator, connections between said mixing chamber and said steam generator so that steam and water may be supplied to said mixing chamber, and a connection between said mixing chamber and the engine crank case so that oil vapor, may be supplied to said mixing chamber.

7. The combination called for in claim 6, wherein said mixing chamber has an air inlet connection, and all mixing chamber connections are fitted with valves.

In testimony whereof I affix my signature.

RUFUS R. ROSS.
